BREECH MECHANISM FOR AUTOMATIC FIREARMS

George Webb, Hartford, Conn., and William L. Swartz, Miami, Fla., assignors to Colt's Manufacturing Company, a corporation of Connecticut

Application November 9, 1945, Serial No. 627,627

8 Claims. (Cl. 89—169)

1

The invention relates particularly to a breech mechanism for a firearm of the type wherein the barrel and the breech structure are permitted to reciprocate bodily as a unit during recoil and counter-recoil, the feeding mechanism in its entirety remaining stationary during such reciprocation. A firearm of the type referred to is disclosed in the patents to Marc Birkigt, Nos. 2,159,-126, 2,159,127, 2,199,871 and 2,199,872.

With a firearm of the type referred to, the breech bolt is longitudinally reciprocable in the breech casing and there is a releasable locking mechanism for holding the bolt in its forward breeched position. For releasing the locking mechanism and for applying force to move the bolt rearward, there is provided a push rod, or preferably two push rods, movable rearwardly upon firing. Heretofore these push rods have been actuated by a gas operated means receiving gases of explosion from the barrel, the said gases reacting upon a piston which in turn moved the push rods by means of suitable mechanical connections. The gas operated mechanism has been frequently found objectionable on account of clogging of the gas passages, or on account of sticking of the piston with resultant delayed action, or for other reasons. Furthermore, with a gas operated mechanism the rate of rearward movement of the push rods has no fixed or determined relationship to the rate of rearward recoil movement of the barrel and casing.

The principal object of the present invention is to eliminate the gas operated mechanism with its inherent objections, and to provide for the same purpose a simple and positively acting mechanical device, which will reliably actuate the release mechanism for the lock and also move the bolt rearward whenever recoil movement occurs.

A further object of the invention is to insure movement of the push rods in definitely timed relationship with the rearward recoil movement of the barrel and casing.

A still further object of the invention is to provide a gradually accelerated rate of rearward movement of the push rods, such gradually accelerated movement being in definitely timed relationship with the rearward recoil movement of the barrel and casing.

Other objects of the invention will be apparent from the accompanying drawing and from the following specification and claims.

Of the drawing:

Fig. 1 is a side view of a firearm embodying the invention, the feed mechanism being omitted and certain portions of the firearm being broken

2

away with other portions shown in section along the line 1—1 of Fig. 2.

Fig. 2 is a plan view of the firearm shown in Fig. 1 with certain portions shown in section along the line 2—2 of Fig. 1.

Fig. 3 is an enlarged fragmentary view similar to Fig. 1 but showing the parts in different relative positions.

Fig. 4 is a front view of the lock release mechanism to which the invention particularly relates, the casing being omitted and the barrel being shown in dot-and-dash lines.

Fig. 5 is a vertical sectional view taken along the line 5—5 of Fig. 4.

Fig. 6 is a vertical sectional view taken along the line 6—6 of Fig. 4.

Fig. 7 is a view similar to Fig. 5 but showing an alternative construction.

Referring to the drawing, 11 and 12 represent respectively the barrel and the breech casing of a firearm of the type to which the invention is particularly applicable. In use, the firearm is so mounted that the barrel and the breech casing can reciprocate longitudinally as an entirety when firing occurs.

Carried by the casing 12 and in slidably engagement therewith is a slide member 13 which is adapted to carry a suitable feed mechanism or magazine, not shown. By means to be described, the slide member 13 is held stationary notwithstanding reciprocation of the barrel and casing. The feed mechanism is detachably connected with the slide 13, having a portion adapted to be engaged under a hook 14 and having another portion adapted to be engaged by a latch 15 controlled by a lever 16.

Positioned within the casing 12 is a breech bolt 17 which is longitudinally reciprocable relatively to the casing. A releasable lock is provided for holding the bolt 17 in its forward breeched position and, as shown, this lock includes a strut 18 pivotally engaged at its forward end with the bolt and seated at its rear end in a notch in a transverse member 19 carried by the casing. Positioned at opposite sides of the breech bolt 17 and guided for longitudinal movement separate therefrom are two unlocking plates 20, 20. The plates 20, 20 are tied together by a cross member 21 which extends through a slot 22 in the bolt 17, the width of the slot being greater than the width of the cross member. Each plate 20 has a notch 23 having a rearward facing cam surface, and the strut 18 has upward projecting hooks 24 projecting into the notches 23 and having forward facing cam surfaces adapted to engage with the

rearward cam surfaces of the notches. When the plates 20 are in their forward positions as shown in Figs. 1 and 2, the rear end of the strut 18 is seated in the notch in the transverse member 19 and the bolt 17 is locked in its forward breeched position. The cross member 21 is at the front of the slot 22. However, when the plates 20 are moved rearward relatively to the breech bolt, the before-mentioned cam surfaces engage each other with the result that the strut 18 is swung upward to the position shown in Fig. 3, being thus removed from the notch and being free to move rearward over the top of the member 19. The bolt 17 is thus unlocked and can move rearward upon recoil. Rearward movement of the plates 20, 20 with respect to the bolt 17 is limited by engagement of the cross member 21 with the rear of the slot 22. Upon counter-recoil the bolt returns to its forward breeched position and the strut 18 returns to the locking position as shown in Fig. 1.

For moving the plates 20, 20 there are provided two push rods 25, 25 which are carried by the casing and which are longitudinally movable relatively thereto. Each push rod abuts at its rear against the front of the corresponding unlocking plate 20. It will be observed that the push rods 25, 25 serve not only to effect unlocking as described, but also serve after the plates 20, 20 have reached their limit of rearward relative movement to apply pressure to the bolt to insure its rapid rearward movement in the breech casing 12.

The mechanism as thus far described is old in the art and does not of itself constitute any part of the present invention. Two separate plates 20, 20 and two separate push rods 25, 25 are commonly used and are preferred, but the invention is not necessarily so limited. However, the novel mechanism to be now described is adapted for use with two push rods; and this is the mechanism preferred.

It has already been stated that the barrel and the breech casing are longitudinally reciprocable upon firing, and that the slide member 13 is held stationary notwithstanding the reciprocatory movement of the barrel and casing. In accordance with the present invention, the relative movement of the casing with respect to the slide member upon firing is utilized to move the push rods longitudinally so as to effect the release of the lock. When two transversely spaced push rods 25, 25 are provided as is preferred, there are provided two transversely spaced levers 26, 26 each having between its ends a pivot aperture for receiving a transverse pivot pin 27 carried by the reciprocable casing 12 and each engaging at 28 near its lower end with the corresponding push rod 25. Each lever 26 has a slot 29 near its upper end for receiving a stationary pivot pin 30 carried by or connected with the stationary slide 13. The result is that when the casing 12 moves rearward during recoil the pivotal connection at 27 moves rearward, and inasmuch as the pivotal connection at 30 is stationary the levers 26, 26 move in the clockwise direction about the pivotal axis at 27 and serve to push the rods 25, 25 toward the rear to effect unlocking as shown in Fig. 3. When the casing moves forward during counter-recoil, the levers 26, 26 are restored to the positions shown in Fig. 1 and the push rods 25, 25 are free to move forward to the position shown in that figure.

It will be seen that in view of the described

mechanical actuating means for the push rods, the said rods are moved in definite predetermined timed relationship with the recoil movement of the barrel and casing. Thus the unlocking and the initial movement of the bolt are effected in timed relation to the recoil movement.

A lug or projection 31 extends upward from the top of the casing at the front end thereof and a bracket 32 is secured to the forward face of this lug, the said bracket carrying the pivot pin 27. Two forward extending brackets 33, 33 are secured by cap screws 34, 34 to the slide 13 at opposite sides thereof, these brackets near their forward ends carrying the transverse pivot pin 30. Preferably, the brackets 33, 33 are utilized for maintaining the slide 13 stationary. To this end the brackets are provided respectively with laterally projecting lugs 35, 35 which are engaged by longitudinally extending tie rods 36, 36, the forward ends of which are secured to a stationary portion of the mount for the firearm.

In order to hold the pivot pin 30 securely in place and to assist the brackets 33, 33 in preventing relative upward movement thereof, the said pin carries a roller 37. A bracket 38 is secured to the rear face of the lug 31 and this bracket has a portion which extends forward and is immediately above the roller 37. It will be seen that the bracket 38 moves with the casing and therefore moves relatively to the roller 37, the axis of which is stationary. The roller engaging face of the bracket 38 is horizontal and the bracket therefore serves to prevent upward movement of the roller and thus serves to more securely hold the pivot pin 30.

Preferably and as shown, the bracket 32 carries a threaded stud 39 which projects rearward through a central opening in the lug 31 and into an opening in the lower rear portion of the bracket 38. Keys 40 prevent the bracket 32 from turning about the axis of the stud. A nut 41 engages the rear portion of the stud and also the bracket 38, the stud and nut thus serving to hold in place both of the brackets 32 and 38. The bracket 32 is shown as having an integral flange 42 which extends along one side of the lug 31, and is provided with a hole 43. This bracket has no function for the operation of the push rods, but serves to carry a member, not shown, for operating the feed mechanism.

In Fig. 7 there is shown an alternative construction wherein levers 44 are substituted for the levers 26. Each lever 44 has a bearing aperture 55 for receiving the pivot pin 30 and has a longitudinal slot 45 for receiving the pivot pin 27. It will be seen that when the lever 44 moves from the position shown in Fig. 7, to a position corresponding to that shown in Fig. 3, there is a gradual reduction of the length of the lever arm represented by the distance between the pivot pins 30 and 27 and a gradual increase of the length of the lever arm represented by the distance between the pivot pin 27 and the point of engagement at 28 with the push rod. This gradual change in the relationship between the lengths of the two lever arms causes a gradual acceleration of the rate of movement of the push rod relative to the rate of movement of the barrel and casing.

Preferably each slot 45, while generally longitudinal, is at an angle to a line connecting the axis of the pin 27 and the axis of the pin 30 which is initially in the lower end of the slot,

all as shown in Fig. 7, the upper part of the said slot being forward of the said line. It will be seen that the inclined position of the slot 45 with the resultant forward position of the upper end thereof causes increased rearward movement of the lower end of the lever at 28 with corresponding increased rearward movement and increased acceleration of the corresponding push rod 25.

What is claimed is:

1. An automatic firearm comprising in combination, a breech casing and a barrel longitudinally reciprocable upon firing, a slide member having slidable engagement with the casing, means for holding the slide member stationary notwithstanding reciprocation of the casing and barrel, a breech bolt in the casing and longitudinally reciprocable relatively thereto, a releasable lock for holding the bolt in its forward breeched position, means for releasing the lock including a push rod carried by the casing and longitudinally movable relatively thereto, a lever having between its ends a pivotal connection with the reciprocable casing and engaging near its lower end with the push rod, and means connected with the stationary slide member and having pivotal connection with the lever near its upper end whereby upon recoil movement of the casing the lever is moved about its first said pivotal connection to move the push rod and thereby release the lock.

2. An automatic firearm comprising in combination a breech casing and a barrel longitudinally reciprocable upon firing, a slide member having slidable engagement with the casing, means for holding the slide member stationary notwithstanding reciprocation of the casing and barrel, a breech bolt in the casing and longitudinally reciprocable relatively thereto, a releasable lock for holding the bolt in its forward breeched position, means for releasing the lock including a push rod carried by the casing and longitudinally movable relatively thereto, a lever having between its ends a pivotal connection with the reciprocable casing and engaging near its lower end with the push rod, and means connected with the stationary slide member and having pivotal connection with the lever near its upper end whereby upon recoil movement of the casing the lever is moved about its first said pivotal connection to move the push rod and thereby release the lock, one of said pivotal connections to the lever being slidable upon recoil of the casing to increase as the casing recoils upon firing the ratio of the distance between said pivotal connection to the stationary slide member and the push rod engaging portion to the distance between said pivotal connection to the stationary slide member and the pivotal connection with the reciprocable casing.

3. An automatic firearm comprising in combination, a breech casing and a barrel longitudinally reciprocable upon firing, a slide member having slidable engagement with the casing, means for holding the slide member stationary notwithstanding reciprocation of the casing and barrel, a breech bolt in the casing and longitudinally reciprocable relatively thereto, a releasable lock for holding the bolt in its forward breeched position, means for releasing the lock and for moving the breech bolt rearwardly, such means including a push rod carried by the casing and longitudinally movable relatively thereto, a lever having between its ends a fixed pivotal connection with the reciprocable casing and engaging near its lower end with the push rod, the said

lever having a longitudinal slot in its upper end portion, and a stationary pivot pin connected with the stationary slide member and entering the said slot in the lever whereby upon recoil movement of the casing the lever is moved about its said pivotal connection to move the push rod and thereby release the lock.

4. An automatic firearm comprising in combination, a breech casing and a barrel longitudinally reciprocable upon firing, a slide member having slidable engagement with the casing, means for holding the slide member stationary notwithstanding reciprocation of the casing and barrel, a breech bolt in the casing and longitudinally reciprocable relatively thereto, a releasable lock for holding the bolt in its forward breeched position, means for releasing the lock and for moving the breech bolt rearwardly, such means including a push rod carried by the casing and longitudinally movable relatively thereto, a lever having a pivot aperture near its upper end and having a generally longitudinal slot between its ends and the said lever engaging near its lower end with the push rod, a pivot pin carried by the reciprocable casing and entering the slot in the lever, and a stationary pivot pin carried by the stationary slide member and entering the pivot aperture in the lever whereby upon recoil movement of the casing the lever is moved about the movable pivotal connection formed by the first pivot pin and the slot to move the push rod at a rate gradually accelerated with respect to the rate of movement of the casing and barrel.

5. An automatic firearm comprising in combination, a breech casing and a barrel longitudinally reciprocable upon firing, a slide member having slidable engagement with the casing, means for holding the slide member stationary notwithstanding reciprocation of the casing and barrel, a breech bolt in the casing and longitudinally reciprocable relatively thereto, a releasable lock for holding the bolt in its forward breeched position, means for releasing the lock and for moving the breech bolt rearwardly, such means including a push rod carried by the casing and longitudinally movable relatively thereto, a lever having a pivot aperture near its upper end and having a generally longitudinal slot between its ends and the said lever engaging near its lower end with the push rod, the said slot being inclined forwardly from a line extending through the pivot aperture and the lower end of the slot, a pivot pin carried by the reciprocable casing and entering the slot in the lever, and a stationary pivot pin carried by the stationary slide member and entering the pivot aperture in the lever whereby upon recoil movement of the casing the lever is moved about the movable pivotal connection formed by the first pivot pin and the slot to move the push rod at a rate gradually accelerated with respect to the rate of movement of the casing and barrel.

6. An automatic firearm comprising in combination, a breech casing and a barrel longitudinally reciprocable upon firing, a slide member having slidable engagement with the casing, means for holding the slide member stationary notwithstanding reciprocation of the casing and barrel, a breech bolt in the casing and longitudinally reciprocable relatively thereto, a releasable lock for holding the bolt in its forward breeched position, means for releasing the lock including two transversely spaced push rods carried by the casing and longitudinally movable relatively thereto, a projection on the reciprocable

easing carrying a transverse pivot pin, two brackets connected with the stationary slide member and carrying a transverse pivot pin above the first said pivot pin, and two transversely spaced levers each having between its ends a pivot aperture receiving the first said pivot pin and each having in its upper end portion a slot receiving the second said pivot pin, the said levers engaging near their lower ends with the respective push rods whereby the push rods are moved to release the lock upon recoil movement of the casing with resultant movement of the levers about the first said pivot pin.

7. An automatic firearm comprising in combination, a breech casing and a barrel longitudinally reciprocable upon firing, a slide member having slideable engagement with the casing, transversely spaced forward extending brackets on the slide, means engaging the brackets for holding the slide member stationary notwithstanding reciprocation of the casing and barrel, a breech bolt in the casing and longitudinally reciprocable relatively thereto, a releasable lock for holding the bolt in its forward breeched position, means for releasing the lock including two transversely spaced push rods carried by the casing and longitudinally movable relatively thereto, a projection on the reciprocable casing carrying a transverse pivot pin, a transverse pivot pin above the first said pivot pin and carried by the said brackets, and two transversely spaced levers each having between its ends a pivot aperture receiving the first said pivot pin and each having in its upper end portion a slot receiving the second said pivot pin, the said levers engaging near their lower ends with the respective push rods whereby the push rods are moved to release the lock upon recoil movement of the casing with resultant movement of the levers about the first said pivot pin.

8. An automatic firearm comprising in combi-

nation, a breech casing and a barrel longitudinally reciprocable upon firing, a slide member having slideable engagement with the casing, means for holding the said member stationary notwithstanding reciprocation of the casing and barrel, a breech bolt in the casing and longitudinally reciprocable relatively thereto, a releasable lock for holding the bolt in its forward breeched position, means for releasing the lock including two transversely spaced push rods carried by the casing and longitudinally movable relatively thereto, a projection on the reciprocable casing carrying a transverse pivot pin, two brackets connected with the stationary slide member and carrying a transverse pivot pin above the first said pivot pin, two transversely spaced levers each having between its ends a pivot aperture receiving the first said pivot pin and each having in its upper end portion a slot receiving the second said pivot pin, the said levers engaging near their lower ends with the respective push rods whereby the push rods are moved to release the lock upon recoil movement of the casing with resultant movement of the levers about the first said pivot pin, a roller on the second said pivot pin, and a guide carried by the casing and positioned above the roller to engage it and prevent upward movement of the second said pivot pin.
